APPARATUS FOR CONTROLLING BACKWATER
IN SEWER LINES

Deno Del Vecchio, Chicago, Ill.

Application February 12, 1958, Serial No. 714,779

8 Claims. (Cl. 137—115)

This invention relates to flood control apparatus. In particular it has relation to apparatus which is adapted to be inserted in a branch sewer line from building premises to the street main for preventing damage to the premises by backwater resulting from a flood condition which overloads the main.

In many communities the rapid increase of buildings for residences and industrial use has far exceeded the rate contemplated when the sewage system of the community was laid out. As a result the sewage main, in many localities, is operating very nearly at full capacity during normal conditions of rainfall. Consequently unusual precipitation may overtax the main and water will back up through the branches to flood the premises.

To circumvent such occurrences it has been the practice of the owner to break out a section of the branch line and to install therein a device which, while allowing or facilitating normal flow of waste from the premises to the main, functions automatically upon occurrence of backwater, to prevent the same from entering the sanitary system of the premises whereby to cause damage. In general, a check valve responsive to rising level of backwater closes when such level becomes dangerous.

Many of these devices also include an automatically-operating pump, operable when the check valve is closed, to receive the building waste and to deliver it to the street side of the apparatus against the prevailing head of backwater.

The present invention relates to improvements in apparatus of the foregoing character.

A principal object of the invention is to provide, in a flood control device which includes a compartment containing a valve for closing the building side of the sanitary system to backwater, a separate compartment containing a pump for receiving waste during closure of the valve and forcing the same into the street side of the sewer system, and venting means in the pump-containing compartment capable of venting both compartments but operable in response to water level in the valve-containing compartment.

Another object is to provide an automatically operable, dual valve mechanism one of which valves will, upon occurrence of flood water, open both said compartments of the apparatus to atmosphere to prevent air lock and the other of which will close to control the level at which the pump starts to operate.

Still another object is to utilize the second mentioned valve in a manner to regulate performance of the apparatus in accordance with predetermined water levels therein in order to avoid unnecessarily frequent pump operations when the backwater condition is not of dangerous extent.

A further object is to provide in a flood control device a swinging, float-operated valve for closing the building side of the sewer main to influx of backwater which includes a novel linkage for obtaining maximum closing force from the float.

Other objects and advantages of the invention will be

2

come apparent from the ensuing description which, taken with the accompanying drawings, discloses a preferred form the invention may assume in practice.

In this drawing:

5 Fig. 1 is a top plan view of apparatus in accordance with the invention, with the cover removed;

Fig. 2 is a cross section thereof taken on the line 2—2 of Fig. 1;

Fig. 3 is a cross section taken on the line 3—3 of Fig. 1.

10 Fig. 4 is a partial top plan view showing the inlet connection to the apparatus;

Fig. 5 is a cross section taken on the line 5—5 of Fig. 1;

Fig. 6 is a detail of the vent valve between the main valve chamber and the pump chamber;

Fig. 10 is a cross section taken on the line 10—10 of 15 Fig. 9;

Fig. 11 is a detail in side elevation of an alternative vent valve capable of joint operation with the alternative main valve of Fig. 9;

Fig. 12 is a top plan view of the detail of Fig. 11; 20 and

Fig. 13 is a cross section taken on the line 13—13 of Fig. 12.

Broadly regarded the invention comprises a casing including a top wall, a bottom wall and side walls together with a transverse partition therein defining what will be termed a main valve compartment and a pump compartment within said casing. The sewage line carrying the waste from the premises enters the main valve compartment for normal delivery of the waste thereinto. During a flood condition the main valve is closed automatically and the waste is alternatively delivered into the pump compartment by means of a Y-connection whereupon the pump therein is started automatically to forcibly deliver the waste to the street side of the main valve compartment against the static head of backwater therein. In either event the waste leaves the apparatus through another opening in the main valve compartment. The main valve is preferably arranged to be float-operated and to close when the water in the valve compartment reaches a predetermined level corresponding to a dangerous backwater condition. However, when the level is such as to correspond to normal transmission of waste through the compartment the valve is maintained open by counterbalance means. The pump contained in the pump compartment is arranged to be started in response to a predetermined level of fluid therein corresponding to a supply of waste to be delivered to the main valve compartment against the head of backwater therein. To this end flow from the incoming sewer line is, as stated, 45 diverted to the pump compartment via a Y-branch. A flap or other suitable valve responsive simply to pressure differential is located in the partition separating the main valve compartment from the pump compartment and adjacent the upper margin of the partition in order that the air pressure created by rising flood water in the valve compartment may be relieved to the pump compartment and thence to atmosphere through a vent valve therein. When flood water submerges the relief valve located in the partition the same is closed. During normal periods, 50 i.e., in the absence of backwater, a second vent valve connected to atmosphere is maintained closed by the action of a second float and valve disc movable therewith, this latter being arranged to open and close a port connecting the two compartments. However, when the level in the main valve compartment reaches a predetermined level this second float is raised thereby closing its port and concurrently opening the atmospheric vent

55 60 65 70 75 80 85 90 95

valve. In this way the vent located in the pump compartment, where it may serve both compartments, is operated by liquid level in the main valve compartment while the main valve compartment is isolated from the pump compartment to confine the backwater therein following opening of this vent valve. In the absence of flood water the flow of waste from the premises into the apparatus is principally into the main valve compartment. However, if any portion thereof should pass through the side branch of the Y-connection and into the pump compartment the same may leave through the said port in the partition which, as stated, is open in the absence of flood water, and the waste then leaves the apparatus through the sewer outlet from the main valve compartment. During prevalence of a flood condition all building waste is delivered to the pump compartment and from there into the main valve compartment against the head of water therein. Eventually the waste is carried to the main upon subsidence of the flood condition.

Adverting to the drawings I have shown apparatus in accordance with the invention comprising a casing 10 of sheet steel suitably coated to inhibit rust. The same includes a rear wall 11, a front wall 12, a side wall 13, a right side wall 14, a left bottom consisting of a portion 15 of trough-like configuration and a portion 16 of similar configuration, and a detachable cover 18. This latter may be secured to a flanged margin 21 at the top of the casing by any suitable means, e.g. bolts or screws 22 and a gasket 23 is interposed, all as is common in this art.

A partition 25 divides the casing into a main valve compartment 28 and a pump compartment 29. Desirably the partition 25 is sealed with respect to the cover 18 by a flange 31 thereon functioning similarly to the flanged margin 21. The trough-like configuration of the floor portion of each compartment facilitates cleaning.

The wall 11 is provided with a ferrule 41 defining an opening 42 for admitting the building waste to the rear side of the main valve via the incoming sewer line 43. The joint is suitably caulked. At this juncture it will be apparent that, in the case of an interior installation, the apparatus is received in an excavation below the basement floor and, in the case of an outdoor installation, below the ground. In either instance a cover is provided at floor or ground elevation for access to the apparatus. Effluent from the apparatus passes to the street main via a branch line 46 fitted over a ferrule 47 defining an exit opening 48.

During normal conditions, i.e. in the absence of flood water, waste from the premises flows in the direction of the arrows through the open main valve and the compartment 28 to the street main. Upon occurrence of backwater, flow in the line 46 is reversed and the level in the main valve compartment 28 will rise. In one practical embodiment of the invention a level of approximately 3" in the compartment will begin to actuate the main valve now to be described.

A valve disc 51 of resilient material, e.g. rubber, is supported on a rigid disc 52 which is, in turn, carried on an arm 53 comprising a pair of identical parallel, spaced-apart, formed wire elements. These latter are provided with eyes secured to a shaft 55 pivoted in a pair of end bearings 56 secured to the wall 13 and partition 25 respectively.

A pair of floats 61 are united by a bar 62 which is received in the eyeletted ends of a lever 63 which, like the arm 53, comprises a pair of identical, parallel, spaced-apart, formed wire elements pivoted for joint rotation on a shaft 65 carried in a pair of bearings 66 mounted on the wall 13 and partition 25 respectively.

A formed wire link 68 is pivotally connected by its ends to the lever 63 and arm 53. Thus, upon upward movement of the floats 61 in response to rising water level, the valve disc 51 is brought into obturating relation with its seat, viz. the adjacent perimeter of the ferrule 41 and

the valve will remain closed until the water subsides to the predetermined level. By such action flood water is prevented from passing into the branch 43 and damage to the premises is thereby avoided.

As the water level rises in the compartment 28 venting of air therefrom must be accelerated for otherwise closing of the valve cannot be accomplished at a sufficiently rapid rate and a gush of flood water may enter the premises before the valve may be fully closed. To this end and as part of the means for venting the compartment 28 (Fig. 6) the partition 25 is provided adjacent its upper margin with a port 71, and a flexible diaphragm 72 is positioned thereover and supported by screws 73. Diaphragm 72 is slightly bowed in the direction of the compartment 28 and some play is allowed between the same and the screws 73. The fit is of such nature that air may be forced below the diaphragm and through the port 71 but, when covered by water, the port is closed by the head thereof. Consequently venting of the main valve compartment 28 to the pump compartment 29 is accomplished rapidly and automatically by extremely simple and reliable means. As will subsequently appear, the foregoing venting arrangement is supplemented by additional venting means.

During a flood condition and notwithstanding closure of the main valve the apparatus functions to receive building waste and to deliver the same against the static head of backwater in the compartment 28 forwardly of the main valve. To this end means are provided to divert flow of waste from the branch line 43 through a branch comprising a T connection 76 and an elbow 77 or any other equivalent Y-connection. Compartment 29 is provided with a ferrule 81 in the wall 11 over which the elbow 77 is fitted and caulked. A strainer or screen 82 confronting the ferrule 81 prevents paper and other objects flowing with the sewage and not of readily disintegrative character from fouling the pump.

The compartment 29 houses a common type of pump 91, preferably of the centrifugal type with a totally enclosed electric motor, provided with an inlet port (not shown) adjacent the lower end thereof and arranged to be started and stopped by any suitable switch 90 responsive to water level or head, e.g. a switch operated by a bellows or diaphragm responsive to water pressure or by a float responsive to water level. In the example the pump is initiated into rotation when the level in the compartment 29 reaches approximately 6". The discharge line 92 of the pump exits in a sub-compartment 94 (Fig. 7) including a bottom wall 95 having a conventional spud 96 for attachment of the pump discharge, two side walls 97 and a top wall 98. The remaining side wall is a part of the wall 12 and the entire sub-compartment is secured in a lower corner of the compartment 29, as shown, in alignment with an opening 101 in the partition 25 whereby the sub-compartment is placed in fluid communication with the compartment 28. The top wall 98 has an opening 103 providing communication between the compartments 28 and 29 via the opening 101.

The exit of the pump discharge 92 into the sub-compartment 94 is provided with a one-way flap valve 99 (Figs. 7 and 8) secured to the bottom wall 95 by means of a screw-fastened cleat 100. As long as the pump is not operating the valve 99 remains closed whereby to prevent back-flow of waste from the compartment 28 to the compartment 29.

A rod 105 carries, at one end, a float 106 movable in a vertical path in response to water level in the compartment 28. The rod 105 also carries, by means of nuts 107, a flexible valve disc 108 backed by a rigid disc 109 adapted, when the float 106 rises, to close the opening 103 and simultaneously to open a vent to atmosphere now to be described.

The wall 14 of the casing 10 is provided with an opening 121 in communication with a vent pipe 123

carried to atmosphere in any convenient arrangement. Normally, i.e. in the absence of backwater the opening 121 is closed by a flexible disc 124 carried on a rigid disc 125 at the distal end of one arm 126 of a bell crank 127 pivoted at 128 to a bracket mounted on the wall 14. A link 132 parallel to the other arm 133 of the bell crank 127 is pivoted at one end to a bracket mounted on the wall 14 and has its opposite end pivoted at 135 to an end of one arm 136 of an operating member 137. The other arm 139 has its distal end secured to the rod 105. Thus, when the float 106 rises, the valve 124 is opened through the parallelogrammatic linkage constituted by the arms 132, 133 and 136, and vice versa.

By means of the arrangement just described a rising level in the compartment 28 is effective to open the vent 123 in the other compartment 29 and, by seating of the disc 108 over the opening 103, to concurrently seal the latter compartment against entry of backwater. Concurrently, and as referred to hereinabove, the main valve is in process of being closed to prevent backwater from entering the sanitary system of the premises. To obtain this sequence of events it will be noted (Fig. 2) that the float 106 is positioned somewhat lower than the floats 61. During a flood condition waste from the premises may flow into the compartment 29 to be delivered by the pump 91 through the flap valve 99 to the sub-compartment 94 against the static head of backwater therein and thence, via the compartment 28 to the line 46.

Also, by reason of the invention arrangement, air may be vented from the compartment 28 very rapidly as the valve 108 does not close until after the vent valve 124 has been opened. This result is achieved by suitably proportioning the members of the linkage connecting the float 106 to the valve disc 124. Following closure of the valve 108 the port 71 continues the venting function from the compartment 28 to the compartment 29 and thence through the vent pipe 123.

I have found that one of the most important requirements of flood control apparatus of the class here involved is the attainment of extremely rapid venting which, in turn, allows a correspondingly rapid rise of backwater in the apparatus and consequent rapid closing of a main valve. By providing the comparatively large opening 103 air may leave the compartment 28 at an extremely rapid rate, the parts being so proportioned and arranged that the main valve 51 is closed before or at essentially the same time as the valve 108. Any supplementary venting is accommodated by the port 71. Furthermore by reason of the float 106 and the components controlled thereby it is possible to provide an air-venting valve in the pump compartment capable of venting both that compartment and the main valve compartment in response to rising water level in the latter compartment without the use of a mechanical arrangement receiving its input in the main valve compartment and utilizing its output in the pump compartment. Any such arrangement would require a stuffing box in the partition between the compartments and, since a stuffing box has substantial friction not only would a float providing the input have to be disproportionately large but a substantial time lag would be introduced.

As an alternative feature of construction the main valve and the vent valve intermediate the main valve compartment and the pump compartment may be arranged for joint operation. Thus it is assured that both valves open and close simultaneously. It is also desirable to arrange the mechanism for effectuating this purpose as a detachable unit in order that replacement of the same may be accomplished simply by loosening a pair of screws and installing an entirely new unit rather than to effect repairs piecemeal with consequent additional expenditure of time and the possibility of interfering with the necessary coordination of the several moving parts. To this end, and referring to Figs. 9 to 13, there is shown the wall 11 and ferrule 41 as pre-

viously described together with the valve disc 51 and backing plate 52 therefor.

A mounting plate 151 is provided with a pair of key-hole slots 152 to receive a pair of cap screws 153 threadedly engaged in the wall 11 whereby the plate 151 may be rapidly attached and detached as will be understood. A pair of ears 154 are fastened to the plate 151 and are provided with apertures to receive the shaft 156 to the center of which a radial arm 158 is secured. This latter is in turn fastened at its distal end to the plate 52 by means of a bolt 159. Thus the main valve swings between open and closed positions about the axis of the shaft 156.

An L-shaped bracket 161 extends from the plate 151 and carries at its end a lever 162 which is U-shaped in cross section to receive the end of the bracket between the legs thereof, the pivot being indicated at 164. A pair of floats 165 is carried on the lever at one end thereof which function in the same manner as the floats 61 hereinbefore described. At its opposite end the lever 162 is pivotally connected at 166 to a link 167 which is, in turn, pivotally connected at 168 to a rigid arm 169 of the valve arm 158. From the foregoing it will be noted that rising level of water in the main valve compartment will close the valve. To insure positive closure the relationship of the pivotal axes 164 and 166 is so arranged that when the valve is closed the axis 166 falls slightly below the axis 164. Thus the force maintaining the valve closed is applied at an angle of slightly more than 90° but one not so great as to lock the disc with a force which will resist re-opening thereof. Stated otherwise, a toggle-type of locking action is exerted by the buoyant force of the water and reliable seating of the valve disc is assured. The closed position is shown in broken lines.

The valve to provide venting of the valve compartment to the pump compartment is best seen in Figs. 11 to 13. An annular seat 181 is set into an aperture in the partition 25 and is arranged to be closed by a disc 182 supported on one arm of a bell crank 184 pivoted at 185 on a bracket 186 outstanding from the partition 25. The other arm 189 of the crank 184 is pivoted to a link 192 which is connected at its lower end to a crank arm 194 keyed to the shaft 156. Accordingly, it will be evident that closing movement of the main valve is effective to close the vent valve comprising the disc 182 and seat 181. As concerns its basic function the vent valve as just described is similar to the vent valve 72.

While I have shown a particular embodiment of my invention, it will be understood, of course, that I do not wish to be limited thereto since many modifications may be made and I, therefore, contemplate by the appended claims to cover any such modifications as fall within the true spirit and scope of my invention.

55 I claim:

1. Apparatus for controlling backwater in sewer lines adapted to be interposed in a branch line from building premises to a street main comprising: a casing having a bottom wall, a top wall, side walls and a transverse partition defining a main valve compartment and a pump compartment, means providing an inlet for effluent from that portion of the branch line between the premises and the apparatus to the main valve compartment, means providing an outlet for effluent from the main valve compartment to the street main, a main valve in said main valve compartment intermediate said inlet means and outlet means for isolating said inlet means from said outlet means, first float means for closing and opening said valve in response to rising and falling level of backwater in said main valve compartment respectively, passage means interconnected with said branch line portion providing an inlet to said pump compartment for alternate flow of said effluent thereto when said valve is closed, a pump having an intake port and a discharge port, said pump being located in said pump compartment

having its intake port therein, means responsive to rising and falling head of water in said pump compartment for starting and stopping said pump respectively; a sub-compartment adjacent said transverse partition and adjacent said bottom wall having a pair of opposed side walls, a single side wall joining said opposed side walls, a top wall and a bottom wall, said sub-compartment walls being joined to said transverse partition, the side of said sub-compartment opposite said single side wall being constituted as an opening in said transverse partition intermediate said main valve and inlet means, the top and bottom sub-compartment walls each having an opening therein, the pump discharge port being connected to the bottom wall opening for delivery of water from said pump compartment to said main valve compartment, second float means movable in said sub-compartment responsive to liquid level common to the space intermediate the main valve and outlet means and the interior of the subcompartment, a closure member for said sub-compartment top wall opening carried by said second float means, a vent line to atmosphere having one end in communication with said pump compartment, a vent valve at said one end for opening and closing said vent line, an operative connection between said second float means and vent valve for opening and closing said vent valve in response to liquid level in the sub-compartment and concurrently moving said closure for opening and closing said top wall opening.

2. Apparatus for controlling backwater in sewer lines adapted to be interposed in a branch line from building premises to a street main comprising: a casing having a top wall, a bottom wall, side walls and partition means between said top and bottom walls defining first and second compartments in said casing, inlet means to said first compartment to pass waste from the premises into said first compartment, outlet means from said first compartment to pass waste therefrom to the street main, a main valve in said first compartment intermediate said inlet and outlet means for isolating the same from each other, means operatively associated with said main valve responsive to rising and falling level of backwater in said first compartment for respectively closing and opening said main valve, passage means between said inlet means and second compartment for alternate flow of waste into said second compartment when said inlet means is isolated from said outlet means by closure of said valve, a pump in said second compartment having an intake port adjacent said bottom wall and a discharge port in communication with said first compartment between said valve and outlet means for delivery of said alternate flow of waste by said pump to the street main against head of backwater, means responsive to rising and falling water level in said second compartment for starting and stopping said pump, a venting passage to atmosphere in said second compartment, valve means for opening and closing said passage, an aperture in said partition means adjacent said bottom wall and between said outlet means and main valve providing communication between said compartments, means responsive to rising and falling level of backwater for closing and opening said aperture to vent said first compartment to said second compartment, said aperture closing-and-opening means being arranged to vent air from said first compartment substantially concurrently with actuation of said main valve to closed position and to terminate venting when said main valve is closed, an operative connection between said passage valve means and aperture closing-and-opening means to move said passage valve means between closed and open positions concurrently with movement of said aperture closing-and-opening means between open and closed positions respectively.

3. Apparatus in accordance with claim 2 wherein said valve closing-and-opening means and said aperture closing-and-opening means are floats, the aperture float being lower than the valve float at their respective lowest

positions whereby movement of the aperture closing-and-opening means to closing position is initiated prior to movement of the valve to closing position and full closure of both occurs substantially simultaneously.

4. Apparatus in accordance with claim 2 further characterized by a second aperture in said partition means adjacent said top wall providing communication between said compartments and closure means operatively associated with said second aperture for venting of air therethrough and for obturating the same upon subjection of said means to head of water.

5. Apparatus in accordance with claim 4 wherein said second aperture is positioned in said partition means between said inlet means and main valve, and said second aperture closure means is located in said first compartment.

6. Apparatus for controlling backwater in sewer lines adapted to be interposed in a branch line from building premises to a street main comprising: a casing having a top wall, a bottom wall, side walls and vertical partition means between said top and bottom walls defining first and second compartments in said casing, inlet means to said first compartment to pass waste from the premises into said first compartment, outlet means from said first compartment to pass waste therefrom to the street main, a main valve in said first compartment intermediate said inlet and outlet means for isolating the same from each other, means operatively associated with said main valve responsive to rising and falling level of backwater in said first compartment for respectively closing and opening said main valve, passage means between said inlet means and second compartment for alternate flow of waste into said second compartment when said inlet means is isolated from said outlet means by closure of said main valve, a pump in said second compartment having an intake port adjacent said bottom wall and a discharge port in communication with said first compartment between said main valve and outlet means for delivery of said alternate flow of waste by said pump to the street main against head of backwater, means responsive to rising and falling water level in said second compartment for starting and stopping said pump, air venting means to atmosphere in said second compartment, an aperture in said partition means adjacent said bottom wall, wall portions defining a sub-compartment surrounding said aperture having a port in one wall portion for flow from said first compartment through said aperture and into said second compartment, valve means for said port, and second float means responsive to rising and falling level of backwater in said first compartment operatively connected to said port-valve means for respectively closing and opening said port.

7. Apparatus in accordance with claim 6 further characterized by means operatively connecting said second float means to said air venting means for opening said vent valve means concurrently with closing action of said port-valve means.

8. Apparatus for controlling backwater in sewer lines adapted to be interposed in a branch line from building premises to a street main comprising: first and second chambers each having substantially co-planar bottom wall portions and common wall means, inlet means for said first chamber for admitting waste from the premises thereto, outlet means for said first chamber for discharge of said waste therefrom to the street main, main valve means in said first chamber adapted to isolate said inlet and said outlet means from each other, means responsive to rising and falling level of backwater for respectively closing and opening said main valve means, a fluid conduit between said inlet means and second chamber for alternate flow of waste into the latter when said main valve means is closed, a pump in said second chamber having an intake port therein to receive said alternate flow and a discharge port connected to said first chamber between said main valve means and outlet means, an

opening in said common wall means adjacent the bottom wall of said first chamber and between said main valve means and outlet means for flow of displaced air from said first chamber to said second chamber, a vent valve in said second chamber for venting air from both chambers, and means responsive to rising and falling level of backwater in said first chamber for respectively closing and opening the said opening in said common wall means.
